UNITED STATES PATENT OFFICE.

EDGAR S. BASSETT, OF CADILLAC, MICHIGAN.

APPARATUS FOR HEATING DWELLING-ROOMS, PUBLIC BUILDINGS, &c.

SPECIFICATION forming part of Letters Patent No. 374,235, dated December 6, 1887.

Application filed April 3, 1886. Serial No. 197,739. (No model.)

To all whom it may concern:

Be it known that I, EDGAR S. BASSETT, of Cadillac, in the county of Wexford and State of Michigan, have invented new and useful Improvements in Heating Apparatus, of which the following is a specification.

In the accompanying drawings, Figure 1 is a perspective view, partly in vertical section, of my improvements applied to a stove. Fig. 2 is a perspective view of the base portion of the apparatus, the outer portion thereof being shown in dotted lines only, so as to more clearly indicate the interior construction. Fig. 3 is a plan view of a modified form of the base portion; and Fig. 4 is a central vertical section of the base shown in Fig. 3, the position of a stove thereon being indicated in dotted lines.

The principal feature of the invention consists in a hollow base which is placed upon the floor and upon which the stove or furnace is set. This base has a central chamber, to which ducts or passages lead from the exterior of the base. From this central chamber an upwardly-extending pipe or flue leads, which carries off the air from said central chamber and induces a draft through the base.

Referring first to Figs. 1 and 2, A is the hollow base, having an interior central chamber, D. Extending from the outer walls of the base to the central chamber are a series of open passages or ducts, 1 2 3, &c., which establish communication between the exterior air and the central chamber. The extent of the openings of the ducts may be varied at pleasure, so as to control the admission of air to the central chamber, by means of sliding valve-bars I I, one for each set of ducts shown, each bar having a series of ports, e e, corresponding in number and relative position with the ducts. By sliding the bars in and out the size of the openings of the ducts may be varied.

Upon the base A is placed a stove, S, of any desired construction. The products of combustion from the stove pass to the exit-flue F through an enlarged casing, L. Within this casing is a hot-air drum, H, from the upper end of which there extends through the wall of the casing an exit-flue, M, which conveys the heated air to any desired locality. The lower portion of the drum H communicates by a flue, C, with the central chamber, D, of the

hollow base. The cold air from the floor passes through the hollow base to the heating-drum, where it is heated and conveyed away, the described construction insuring a strong draft of air through the base and drum, thus causing a rapid circulation of air in the apartment in which the stove is placed and insuring a more equable temperature throughout the apartment.

The drum H is held within the casing L at the bottom by a ring, k, and supports a a', attached to the ring and resting on the inner wall of the casing and attached thereto. The supporting ring k is unconnected to the drum, the lower conical end of the drum extending therein sufficiently to hold it in place. Braces b b at the top, interposed between the casing and drum, hold the latter in proper central position.

To facilitate the heating of the air in the drum, and to check the too rapid escape of the products of combustion from the stove through the casing, the drum is contracted at its center, as shown, and encircling its contracted portion is a horizontal annular shelf, E, fixed to the casing. This shelf deflects the upward currents of the products of combustion against the drum, thus facilitating the heating thereof.

In Figs. 3 and 4 is shown a modification of the invention applicable to a heating-stove designed to heat only the apartment in which the stove is placed. In these figures a circular instead of a rectangular base is shown, and the air passing through the base is conveyed not to a drum, but to the bottom of the stove, the air rising therefrom along the exterior surface of the stove. In this case the central chamber is at the center of the circular base, and the air-ducts lead radially from the entire periphery of the base to the central chamber. The sliding valve-bars are in this case replaced by a circular valve-ring, J, encircling the periphery of the base. In other respects the construction and function of the ring J are similar to the valve-bars I I.

The central chamber is open at the top, and above it is arranged a vertically-movable drum, B, the upper open mouth of which is immediately beneath the bottom of the stove.

The position of the drum B may be adjusted by set-screws O O', which bear against a circu-

lar rim or flange, R, on the base. This arm is the equivalent of the conducting-flue C in the first-described construction.

I claim as my invention—

- 5 1. A hollow base for stoves and furnaces, the same having a central chamber, ducts leading from the exterior of the base to said central chamber, and an outlet-passage leading upwardly from said central chamber, substantially as set forth.
- 10 2. A hollow base for stoves and furnaces, the same having a central chamber, and ducts leading from its exterior to said chamber, in combination with valves for controlling the size of the openings of said ducts, substantially as set forth.
- 15 3. A hollow base for stoves and furnaces, the same having a central chamber, and ducts

leading from its exterior to said chamber, in combination with a casing through which the products of combustion from the stove or furnace pass, a hot-air drum within said casing, and a flue leading from said chamber in said hollow base to the lower part of said drum, substantially as set forth. 25

4. The outer casing, the ring *k* therein, and the supports *a a'*, holding said ring centrally in said casing, in combination with the hot-air drum within said casing, having a conical lower end set into said ring, and braces *b b*, interposed between the upper end of the drum and the casing, substantially as set forth. 30

EDGAR S. BASSETT.
